GUN PORT CLOSURE

John H. Buekers, Jr., Detroit, Mich.

Application October 12, 1931, Serial No. 568,370

4 Claims. (Cl. 89—36)

The present invention pertains to a novel closure for the gun port formed through a wall member such as a bullet-proof glass partition in a bank or the side of an armored truck. The principal object of the invention is to provide a simple device of this character, readily opened by the thrust of a gun and affording a wide lateral amplitude to a gun inserted in the device.

A further object of the invention is to provide a closure which permits a sighting therethrough and which exerts no downward pressure on the barrel of the gun, so that a short as well as a long gun may be used.

The closure comprises essentially a pair of closure members for the port or opening, pivoted together so that they may be swung relatively to each other or together. These members are preferably spherical on the outside and are formed with flat internal surfaces which converge towards the outside. A gun thrust against either flat surface readily finds its way to the joint between the members and then passes between the members against the action of a spring which tends to hold the members closed against each other. On withdrawal of the gun, the spring brings the members into contact with each other to close the gun port completely.

The invention is fully disclosed by way of example in the following description and in the accompanying drawing in which

Figure 1 is a rear elevation of the device with the back ring removed;

Figure 2 is an elevation of the back ring;

Figure 3 is a horizontal cross section; and

Figure 4 is a vertical cross section.

Reference to these views will now be made by way of like characters which are employed to designate corresponding parts throughout.

The device is applied to a wall 1 which is formed with an opening 2 for receiving the device as will presently appear. The wall may consist of bullet-proof glass, as in a bank, or may be of sheet metal, as on an armored truck.

The frame of the device comprises a ring 3 fitted in the opening 2 and having flange 4 engaging the outer surface of the wall around the opening. A back ring 5 abuts the inner end of the frame ring 3 and engages the inner surface of the wall 1. The ring has tapped bosses 6 on its periphery, and the ring 5 has registering holes 7, so that the parts may be bolted together by studs 8.

Within the frame ring 3 are mounted a pair of substantial octopartite segments 9 which have their ends pivotally attached to the frame ring by studs 11. In order to take the studs and provide

ample metal around the same, the ring 3 has inwardly extending lugs 12 and 13 which are accommodated in slots 14 cut in the back ring 5, as shown in Figure 2. The upper lug 12 is longer and has a depending stud 15 on which is mounted a wire spring 16 coiled at 17 around the adjacent stud 11 and having its free ends 18 inserted in the segments 9 as shown more clearly in Figures 3 and 4. The ends 18 are tensioned towards each other so that they tend to hold the segments 9 in contact with each other and obstructing the opening through the ring 3.

A pointed rib 20 is formed in the ring 3 at the outer side of the segments 9 and presents a conical surface 21 flaring outwardly from the opening. The inner surfaces of the segments 9 are flattened to form plane surfaces 22 converging forwardly or outwardly as may be seen in Figure 3. Finally, the back ring 5 has opposed bevels 23 which converge towards the frame ring 3 as shown in Figure 3.

In the use of the device, the segments 9 are separated for passing a gun 19 therebetween merely by thrusting the gun against either of the surfaces 22. Due to the convergence of the latter, the gun is guided to the joint between the segments and then is forced between them, spreading them apart to the dotted line position shown in Figure 3, against the tension of the spring 16—18. The gun may readily be swung laterally because of the pivotal mounting of the segments on the frame 3 and is permitted a wide lateral range by the conical surface 21 and bevels 23.

The depending stud 15 which supports the spring maintains the closure in a normal centered connection, that is, with the joint in the vertical diameter of the opening. In the absence of such a stud and spring arrangement, the device might be swung open from the outside.

On spreading the segments by forcing a gun therethrough, a vertical opening is provided so that accurate aim may be taken. It will also be seen that the segments now exert equal pressure laterally in opposite directions against the barrel of the gun, so that there is no undue impediment to accurate aiming. This arrangement is to be distinguished from other devices wherein a single upwardly opening flap bears down upon the gun obstructing the proper sight line and in fact prohibiting the use of a short barrelled revolver. A bullet fired against the spherical outer surface of the closure will obviously glance off except in the single case where it might strike the vertical joint. In this as well

as in other cases, there is sufficient metal in the lugs 12 and 13 behind the studs 11 to take the impact.

Although a specific embodiment of the invention has been illustrated and described it will be understood that various alterations in the details of construction may be made without departing from the scope of the invention as indicated by the appended claims.

10. What I claim is

1. A gun port closure comprising a frame member defining an opening, a pair of closure members pivoted to each other and to said frame member and covering said opening, and spring means tending to hold said closure members in contact with each other.

2. A gun port closure comprising a frame member defining an opening, a pair of closure members pivoted to each other and to said frame member and covering said opening, and spring means tending to hold said closure members in

contact with each other, the rear or inner surfaces of said closure members converging to the joint between said members.

3. A gun port closure comprising a frame member defining an opening, a pair of closure members pivoted to each other and to said frame member and covering said opening, and spring means tending to hold said closure members in contact with each other, said members having convexly spherical outer surfaces.

4. A gun port closure comprising a frame member defining an opening, a pair of closure members pivotally connected together in said opening and covering the same, a stud secured to said frame member adjacent the pivotal connection of said closure members, and a spring supported by said stud and entering said closure members, said spring being adjusted to bring said members together and hold them centered in said opening.
